(57) **CLAIM**

The ornamental design for a compliance monitor for a medicament inhaler, as shown and described.

DESCRIPTION

FIG. 1 is a left side view of a compliance monitor for a medicament inhaler of the present invention;

FIG. 2 is a front view thereof;

FIG. 3 is a rear view thereof;

FIG. 4 is a right side view thereof;

FIG. 5 is a top view thereof;

FIG. 6 is a bottom view thereof with two dome switches;

FIG. 7 is a front perspective view thereof, shown with the hinge door opened;

FIG. 8 is a rear perspective view thereof;

FIG. 9 is a front perspective view of the compliance monitor of FIG. 1, shown with a medicament inhaler; and,

FIG. 10 is a rear perspective view thereof.

The broken line showing of the medicament inhaler in FIGS. 9-10 depicts environmental structure and forms no part of the claimed design. All other broken lines depict portions of the compliance monitor for a medicament inhaler that form no part of the claimed design.
